US00D997935S

(12) **United States Design Patent** (10) **Patent No.:** **US D997,935 S**
(45) **Date of Patent:** **** Sep. 5, 2023**

(54) **MONITOR**

(71) Applicant: **Lenovo (Beijing) Co., Ltd.**, Beijing (CN)
(72) Inventor: **Riyi Ling**, Beijing (CN)
(73) Assignee: **Lenovo (Beijing) Co., Ltd.**, Beijing (CN)

(**) Term: **15 Years**

(21) Appl. No.: **35/514,111**

(22) Filed: **Dec. 30, 2021**

(80) **Hague Agreement Data**

Int. Filing Date: **Dec. 30, 2021**

Int. Reg. No.: **DM/220161**

Int. Reg. Date: **Dec. 30, 2021**

Int. Reg. Pub. Date: **Apr. 22, 2022**

(30) **Foreign Application Priority Data**

(57) **CLAIM**

The ornamental design for a monitor, as shown and described.

DESCRIPTION

2.1 is a front view of a monitor showing the new design;
2.2 is a back view thereof;
2.3 is a left view thereof;
2.4 is a right view thereof;
2.5 is a top view thereof;
2.6 is a bottom view thereof;
2.7 is a front, right side perspective view thereof;
2.8 is a back, left side perspective view thereof; and
2.9 is a perspective view showing the monitor in an opened state.

The broken lines shown in the drawings illustrate portions of the monitor that form no part of the claimed design.

1 Claim, 9 Drawing Sheets
